T. B. MOREHOUSE

By Monroe Miller
Attorney.

UNITED STATES PATENT OFFICE.

TERRY BRYAN MOREHOUSE, OF WASHINGTON, DISTRICT OF COLUMBIA.

LOCK.

Application filed June 4, 1923. Serial No. 643,306.

To all whom it may concern:

Be it known that I, TERRY B. MOREHOUSE, a citizen of United States, residing at Washington, District of Columbia, have invented 5 certain new and useful Improvements in Locks, of which the following is a specification, reference being had therein to the accompanying drawing.

The present invention relates to locks, and 10 the primary object of the invention is the provision of a novel and improved lock so constructed and operable that the lock can be quickly and conveniently changed so as to require different keys.

15 With ordinary locks, should a key be lost or misplaced, the finder or wrongful holder of the key can open the lock, and, as a matter of protection, the lock must be replaced by another one. It not infrequently 20 happens that the loss of a key may require the replacement of a number of locks. This is especially true on shipboard, there being a navy requirement that all magazine keys be strictly accounted for and the loss of one 25 magazine key means that the entire set of locks must be replaced. This means from six or more locks on a destroyer to thirty or forty locks on a battleship. The same thing applies to manufacturing plants, warehouses, club lockers, safe deposit boxes, stores, and the like, inasmuch as the loss of a key renders protection insecure, unless the lock is replaced. Also in cases where the 30 keys are in possession of discharged employees, strikers and other unauthorized persons the locks may be opened, so that they must be substituted in order to assure 35 against unauthorized entries.

With ordinary locks, should a key be 40 changed so as to require a different key, after a key has been lost or is in the possession of an unauthorized person, so that the lock can only be opened by the newly selected key, thus preventing the lock from 45 being opened by the former key and rendering the former keys useless. A lock of this kind has a large field of use, as above indicated, inasmuch as key changes can be made whenever desired, such as when a key is lost 50 or in the possession of a discharged employee, striker, or other unauthorized person, or when there is a change of employees,

crews, watchmen, and the like. It is also possible to have key changes made daily or periodically. The lock may also be used for 55 railroad switches and signals so that changes in keys can be made, to prevent disaffected persons and strikers from operating the switches and signals without proper authority. The lock is also useful for tool and 60 work boxes in factories, automobiles, mail and dispatch bags, and for many other purposes; in fact, for almost all uses for which locks are now employed, inasmuch as the 65 present lock will fulfill the requirements of an ordinary lock, with the added provision that key changes can be made whenever desirable or necessary.

Another object of the invention is the 70 provision of such a lock which can be operated by a combination changing key so that upon the insertion of a new key, the lock is changed so as to require the use of the new key to open the lock, and rendering 75 the former keys useless, as well as requiring a new combination changing key to correspond with the new lock opening key. By this arrangement a combination changing key, corresponding with the lock opening key, can be placed away or kept in safe keeping, so that when it is desired to change 80 keys, the combination changing key can be used for setting the lock for the reception of a new key, which when inserted and moved will thereby change the combination of the 85 tumblers, so that the lock can no longer be opened by the previous keys, and requiring the new keys to be used, as well as requiring another combination changing key to correspond with the new key for the purpose of 90 making another change in keys.

The invention has for its more specific objects to provide such a lock which is rugged, 95 foolproof, easy of manipulation, practical and reliable, which does not involve prohibitive complications or mechanism, so that the lock can be manufactured and sold at a cost comparing favorably with ordinary locks now on the market, considering the advantages obtained, and which has novel and 100 improved features of construction that are useful and of advantage.

With the foregoing and other objects in view, which will be apparent as the descrip-

tion proceeds, the invention resides in the construction and arrangement of parts, as hereinafter described and claimed, it being understood that changes can be made within 5 in the scope of what is claimed, without departing from the spirit of the invention.

The invention is illustrated in the accompanying drawings, wherein—

Figure 1 is a median section of the lock, 10 portions being shown in elevation, with the tumblers arranged for one key combination, and the key removed.

Fig. 2 is a view similar to Fig. 1, with the shackle broken away and showing the key 15 inserted and the parts in position for opening the lock.

Fig. 3 is a view similar to Fig. 2 showing the combination changing key inserted preparatory to a change in keys.

Fig. 4 is a similar view showing the lock 20 after being operated by the combination changing key and such key removed for the insertion of a new key to change the combination.

Figs. 5, 6, 7 and 8 are sections on the 25 respective lines 5—5, 6—6, 7—7 and 8—8 of Fig. 1.

As shown, the improvements are embodied 30 in a padlock, but they can be incorporated in cabinet and other types of locks with suitable variations or alterations in adopting the improvements for different conditions, within the scope of what is herein- 35 after claimed.

The case or body of the lock comprises 40 a block 14 over which is fitted the open end portion of a shell or jacket 15, said block and shell being fitted together telescopically, and the block 14 having an outstanding 45 flange 16 against which the edge of the shell 15 abuts. The case or body as shown is of the conventional form of that of the ordinary padlock, and houses and protects the working parts therein. The shell 15 has the 50 lugs 17 and 19 at opposite sides extending inwardly and abutting the block 14, and securing screws 18 and 20 extend through apertures in said lugs and screw into the block 14 to fasten the shell and block together.

The short limb or terminal of the shackle 21 enters the case or body through an aperture 22 in the top of the shell 15, and the long limb or terminal of the shackle extends 55 through an aperture 23 in the top of said shell. The longer limb of the shackle is anchored for sliding and turning movement in the case, said limb having the flat side or cut-away portion 25, and a retainer 60 screw 26 is screwed through the wall of the shell 15 and projects into the case, said screw bearing against the flat side 25 of the shackle to prevent the complete withdrawal of the shackle from the case. At the lower 65 end of the flat side or cut-away portion 25,

the longer limb of the shackle has an annular groove 27, permitting the shackle to be turned when the shorter limb is withdrawn from the case, the groove 27 accommodating the screw 26. The shackle has the collar 28 70 immediately below the groove 27 to contact with the screw 26, when the shorter limb of the shackle is withdrawn from the case, thereby limiting the outward movement of the shackle. The shell 15 has an apertured 75 ear 24 through which the longer limb of the shackle extends, to guide the shackle for sliding and turning movement.

When assembling the parts, the screws 18 and 20 are inserted through the apertures 22 and 23, respectively, the screw 20 passing through the ear 24 also, and after said screws are inserted and screwed home, the shackle 21 is then inserted and the screw 26 applied to the shell, for anchoring the 80 shackle to the case. It will be noted that the screws are inaccessible when the shackle is in closed position, so that the parts of the case cannot be separated unless the shackle 85 is opened.

In order to automatically slide the shackle open, or to separate the shackle and the case, when the shackle is released, a coiled opening spring 30 is confined between the collar 28 of the shackle and the head of the screw 20, the end of the longer limb of the shackle 90 having a finger 29 projecting into said spring. Thus, when the shackle is released, the spring 30 will separate the shackle and case, to withdraw the short limb of the shackle from the case, and the collar 28 contacting with the retainer or stop screw 26, will limit the separation of the shackle and case, and the shackle can then be turned on account of the groove 27 being brought into 100 registration with the screw 26.

The shackle is held in closed position by means of a locking bar or latch 31 disposed immediately under the top of the case, the limbs of the shackle having the notches 32 to receive the opposite ends of said bar or latch. The latch is mounted for oscillatory motion to swing into and out of the notches transversely of the shackle. Thus, the latch 110 31 is engaged between its ends on a pivot pin 33 screwed or otherwise engaged in the top of the case. A wire spring 35' has one end secured in the latch 31, and said spring extends at an angle from the latch and bears 115 against one side of the case, to move the latch to latching position against a stop 34 depending from the top of the case, and said latch can only be disengaged from the shackle by the use of a required key.

A key cylinder 35 is mounted for rotation 120 and axial sliding movement in the block 14, and has a reduced lower or outer end portion 36 extending to the bottom or lower end of the case and forming a shoulder 37 on the cylinder to seat in the block 14 to 130

limit the downward or outward movement of the cylinder. The cylinder has the inner or upper reduced end portion or neck 38 on which a nut or collar 39 is screw-threaded, 5 and an unlocking member 40 is seatable against the nut 39 and end portion 38 of the cylinder. The member 40 has the fingers 41 extending upwardly at an angle toward the top of the case and movable upwardly to overlap the opposite edges of the latch or bar 31 in order to move the latch to releasing position. A clutch connection is provided between the member 40 and cylinder whereby said member and cylinder can 10 be connected and disconnected. Thus, clutch pins 42 are carried by the cylinder, said pins constituting round ended screws engaged between the end portion 38 of the cylinder and the nut 39, and projecting above or beyond said end portion of the cylinder to enter notches or recesses 43 in the lower side 15 of the member 40, to turn said member with the cylinder. Said pins or screws 42 also lock the nut 39 on the cylinder to prevent said nut from loosening. A coiled spring 20 44 is confined between the unlocking member 40 and latch 31 and surrounds the pivot pin 33, to retain said spring in place. The spring presses the latch or locking bar 25 31 against the top of the case, and presses the unlocking member 40 down to engage said member over the clutch pins 42 when the unlocking member and cylinder are turned into registration with one another. The 30 pivot pin 33 is concentric with the cylinder 35, and the unlocking member 40 has a recess 45 to receive the end of the pin 33 when the member 40 is raised the full amount, as seen in Fig. 3. The spring 44 also presses 35 the key cylinder down in the case, and the spring 44 in moving the unlocking member 40 and key cylinder downwardly, will retract the fingers 41 of the unlocking member from the latch 31, whereby the latch is 40 disconnected from the unlocking member and cylinder. When the cylinder is slid inwardly or upwardly within the case, against the tension of the spring 44, the unlocking member 40 is moved to bring the fingers 41 45 in overlapping relation with the latch, at opposite sides thereof, whereby the turning of the cylinder will turn the latch 31 so that the shackle can be released and opened. The unlocking member 40 can also be moved 50 away from the key cylinder, as seen in Fig. 3, to disconnect the unlocking member and key cylinder, for turning the key cylinder to key changing position, by the means of a proper combination changing key, as hereinafter set forth.

The cylinder 35 can only be turned when it is slid into the case, inasmuch as pins or screws 46 which are screw-threaded or otherwise secured in the cylinder project from 55 the shoulder 37 of the cylinder to enter the notches or recesses 47 in the block 14, when the cylinder is slid outwardly and seated in the block 14. Therefore, the cylinder must be slid inwardly to withdraw the pins or screws 46 from the notches 47, before the cylinder can be turned. The pins or screws 46 and notches 47 are diametrically opposite to one another so as to restrain the cylinder against turning movement in either of two 60 reverse positions.

The cylinder 35 has a longitudinal key slot 48 for receiving the key, and the slot can be of different cross sections so as to require keys of corresponding cross sections, as well understood in the art.

In order to prevent the cylinder from being slid inwardly so that it can be turned, without the use of a proper key, a plunger or member 49 is slidable in the block 14 and is connected to the cylinder to slide with the cylinder, so that when said plunger is prevented from sliding by the tumblers, the cylinder cannot be slid into the case to connect the unlocking member 40 with the latch 31 and to turn said latch. The upper end 65 of the plunger 49 is screw-threaded or otherwise secured in a yoke 50 which has a swivel connection with the cylinder, said yoke loosely embracing the neck or reduced end portion 38 of the cylinder and being retained in connection with the cylinder by the nut 39. The plunger 49 must therefore slide with the cylinder, and if the plunger cannot be slid, it will prevent the cylinder from being slid, and the proper key must therefore be used before the cylinder can be shoved inwardly within the case and turned to open the lock.

The sliding movement of the plunger 49 is controlled by the tumblers, as will presently appear. Bores are drilled in the block 14 to intersect the holes or openings in which the plunger and cylinder are disposed, thereby providing the apertures 51 in the partition of the block between the plunger and cylinder, the openings 52 in the block at the opposite side of the plunger, and the recesses 53 at the opposite side of the cylinder. The plunger 49 has the openings 54 to register or aline with the apertures 51 and openings 52, and the cylinder 35 has the radial openings or holes 55 to register or aline with either the apertures 51 or the recesses 53 when the cylinder is turned to reversed positions. Tumbler pins 56 are slidable in the openings 54 of the plunger 49 and are of a length equal to the thickness or width of the plunger, so that said pins can be located entirely within the plunger, to permit the plunger to slide. The tumbler pins 56 are slid into the apertures 51 and opening 55, when free to do so, by means of coiled springs 57 disposed in the openings 52, said springs having caps or end members 58 to contact with the pins 56 and plunger 49.

Tumbler balls 59 are provided to be disposed in the apertures 51, and tumbler balls 60 are provided to be disposed in the opening 55 and recesses 53, and enable various combinations to be set up requiring different keys.

The recesses 53 provide magazines or receptacles for the tumbler balls 60, inasmuch as when the cylinder is turned to bring the 10 openings 55 in registration with the recesses or magazines 53, the balls 60 can be moved into and out of the openings 55 and recesses 63, for selecting different combinations of tumbler balls, as will hereinafter more fully 15 appear. Coiled springs 61 are disposed in the recesses 53 behind the balls to move said balls into the openings 55, and said springs have the caps or end members 62 to contact with the balls 60 and cylinder 35.

20 The key 63 has its edge 64 so cut or formed as to correspond with the numbers of tumbler balls 60 carried by the key cylinder, and said key has a shoulder or lug 65 to abut the outer or lower end of the 25 cylinder to slide the cylinder inwardly. The key 63 is the lock opening or operating key, and the combination changing key 66 has its edge 67 cut or formed to correspond with the edge 64 of the primary key 63, the 30 combination changing key 66 also having a shoulder or lug 68 to contact with the cylinder 35 and move it into the case.

The distinction between the primary or lock opening key and combination changing 35 key is the provision on the key 66 of an extension 69 to project beyond the inner or upper end of the cylinder 35, as seen in Fig. 3, to contact with the unlocking member 40 so as to move said member out of engagement 40 with the clutch pins 42, and permitting the cylinder to be turned independent of the unlocking member, for changing the combination.

The lug 17 has a stop 70 for the contact 45 of the yoke 50 so as to limit the inward movement of the cylinder 35.

When the lock is set for one combination of tumblers, a selected number of balls 60 of the several sets are disposed in the openings 55 of the cylinder, while the other balls 60 are retained in the magazine recesses 53. With the parts in locked position, the shackle 31 or its equivalent is in closed position, with the latch 31 engaging in the 55 notches 32 of the shackle. The key cylinder is moved outwardly and seated in the block 14 with the openings 55 registering with the apertures 51, so that the springs 57 push the tumbler pins 56 into the apertures 51 60 and openings 55, until the innermost balls 60 carried by the cylinder 35 contact with the inner ends of the holes 55, as seen in Fig. 1. The unlocking member 40 is moved from the latch 41 by the spring 44, and the 65 pins 56 projecting out of the plunger 49 into

the block 14 and cylinder 35 will prevent the cylinder and plunger from being slid, as well as preventing the cylinder from turning. Also, the pins or elements 46 of the cylinder seating in the notches 47 will 70 prevent the cylinder from turning.

When the proper unlocking or operating key 63 is inserted in the slot 48 of the cylinder, the balls 60 are forced toward the periphery of the cylinder, thereby bringing 75 the balls 59 into the apertures 51, and moving the pins 56 into the plunger 49, as seen in Fig. 2. This will set the tumblers so that the cylinder can be slid inwardly and turned.

The key 63 is then pushed into the 80 case, so that the lug or shoulder 65 slides the cylinder inwardly, the plunger 49 being free to move with the cylinder, and the pins 46 being withdrawn from the notches 47. The inward movement of the cylinder will therefore release the cylinder for turning movement, and the fingers 41 of the unlocking member 40 will overlap the opposite edges of the latch 31. Then, by turning the cylinder, the member 40 is turned (clock-wise 85 as seen in Fig. 5) so as to turn the latch 31, against the tension of the spring 35', to release the shackle 21. The spring 30 will therefore separate the shackle and case, the screw 26 and collar 28 limiting such separation of the parts, and the short limb of the shackle having been withdrawn from the case, will permit the shackle and case to be

90 turned relatively to one another about the axis of the longer limb of the shackle. The turning movement of the cylinder is limited inasmuch as the unlocking member 40 has but a limited turning movement in the case with the latch 31, so that the cylinder can only be turned through a small angle. 105 When the lock is opened, the corresponding end of the latch 31 bears against the longer limb of the shackle, thereby retaining the latch in releasing position, even though the cylinder 35 is turned back to locking position and the key removed. The lock can 110 therefore be snapped shut or closed, by sliding the shackle into the case, inasmuch as the latch 31 will spring or snap into the notches 32 by the action of the spring 35'. 115 The lock thus performs the usual duty of an ordinary lock, and cannot be picked open or unlocked without the use of the proper key.

In order to change the tumbler combination, the combination changing key 66 must be used, and such key must correspond with the operating or unlocking key 63, so that when the key 66 is inserted in the cylinder, the tumbler pins 56 are shoved back into the plunger 49, the same as when the key 63 is inserted, to permit the cylinder and plunger to be slid into the case. The extension 69 of the key 66 will project beyond the inner end of the cylinder, as seen in Fig. 3, 120 125 130

thereby moving the unlocking member 40 away from the cylinder, so as to open the clutch connection between them, the recess 45 of the member 40 receiving the pin 43 to 5 retain the member 40 in concentric relation with the cylinder. By pushing the key 66 into the case, the shoulder or lug 68 moves the cylinder inwardly, and the unlocking member 40 is moved ahead of the cylinder to 10 keep said unlocking member and cylinder spaced apart. Then, when the screws or elements 46 have been removed from the notches 47, the cylinder can be turned through an angle of 180 degrees to bring the 15 openings 55 into registration with the recesses 53, as seen in Fig. 4. Then, when the combination changing key 66 is withdrawn from the cylinder, the spring 44 presses the unlocking member against the clutch pins 20 42, and the cylinder 35 and plunger 49 are moved downwardly or outwardly. The unlocking member 40 remains seated on the pins 42, inasmuch as the cylinder having been turned through one-half of a revolution, 25 will remove the pins 42 from registration with the notches 43. The unlocking member therefore remains disconnected from the cylinder, excepting that the spring 44 presses the unlocking member against 30 the clutch pins 42. When the key 66 has been withdrawn from the cylinder, the springs 61 force the balls 60 into the openings 55 of the cylinder, as seen in Fig. 4, and the lock is thus prepared for the reception 35 of the new operating or unlocking key. When the new key is inserted, as shown in dotted lines in Fig. 4, the balls 60 are forced into the recesses 53, according to the formation of the edge of the key, and the new 40 key thus selects the numbers of balls 60 of the several sets which are to be carried around by the cylinder, the other balls 60 being retained in the recesses 53. The cylinder is then turned by the new key, after 45 the cylinder is pushed into the lock to remove the screws 46 from the notches 47 to permit the cylinder to turn, so that the balls 60 selected by the new key remain in the openings 55 of the cylinder, while the 50 surplus balls 60 ejected from the cylinder by the new key, remain in the recesses 53. After the cylinder has been turned by the new key to bring the openings 55 adjacent to the apertures 51, the clutch pins 42 will 55 be moved into registration with the notches 43, so that the spring 44 automatically moves the unlocking member 40 into connection with the cylinder, thereby again connecting the unlocking member and cylinder so that 60 the cylinder cannot be turned to combination changing position without the use of a combination changing key, corresponding with the new key that was inserted for changing the combination. Accordingly, 65 when the new key is inserted, the new com-

bination of tumblers is selected, and when the cylinder is turned to normal operative position, the clutch between the unlocking member 40 and cylinder is closed, thereby requiring a new combination changing key 70 corresponding with the new operating key that was used to change the combination. When the new operating or primary key is thus inserted and turned, the lock is then set or changed so as to require the new operating key for operating or opening the lock, and the keys 63 and 66 are therefore useless, unless it is desired later on to change the lock back for the use of the keys 63 and 66. 80

One or more of the keys 63 can be provided for one or more of the locks, and the combination changing key 66 can remain in the possession of an authorized person or may be kept in safe keeping, so that in the event of the loss of one or more of the keys 63 or the possession of operating keys by discharged employees, strikers, or other unauthorized persons, the combination changing key can be used for setting one or more of the locks to combination changing position, and a new key can then be inserted and turned, whereupon the old keys are rendered useless for opening the locks. In this way, by the single insertion, turning 90 movement and withdrawal of the combination changing key, and the insertion and turning movement of the new key, the lock is immediately and quickly changed to require the new key for opening the lock, rendering 100 the previous or old operating key entirely useless for opening the lock. Therefore, instead of substituting the lock or locks, as a protection against persons having keys, whether rightfully or wrongfully in possession thereof, the present lock is such that the lock itself can be changed conveniently and quickly to render the old keys inoperative and to require the newly selected key. It is thus only necessary to change keys instead of changing locks, and several sets of 110 keys can be used for making key changes periodically or whenever circumstances require or warrant such key changes. One lock can thus be used for a large number of different keys, by making key changes through the medium of the combination changing keys, and identically the same lock can be used for different keys, inasmuch as 115 the locks will all have the same number of tumbler balls 60 in the several sets thereof of part of the balls being operative in the cylinders, while the rest of the tumbler balls are held in reserve in the recesses 53 for the purpose of changing the combinations. Manufacture of the locks is thus facilitated, and the locks can be supplied to the users or customers with the key cylinders in key 120 changing position, as seen in Fig. 4, where- 125 by the user or purchaser can select the key 130

that is to be used for opening the lock. Blank operating and combination changing keys can be provided so that new keys can be made by the user or owner of the lock, 5 without others having any knowledge as to the particular key required for opening the lock. The keys for each lock must also be of a cross-section to correspond with the cross-section of the key slot 48 of the cylinder, thereby providing other variations in 10 the keys for different locks.

Having thus described the invention, what is claimed as new is:—

1. In a lock, a key operable member movable to operative and key changing positions, tumbler members to be carried by said key operable member, means for receiving the surplus tumbler members from the key operable member when an operating key is 15 inserted with the key operable member in key changing position, means cooperable with the tumbler members carried by the key operable member when said key operable member is in operative position to prevent said key operable member being operated excepting by the previously selected operating key, and releasable means for preventing the key operable member being moved to key changing position in combination with a combination changing key insertable in said key operable member to control the last named means and tumbler members for moving the key operable member to combination changing position.

2. In a lock, a body, a key operable member movable in said body to operative and key changing positions and having openings, the body having recesses for the registration of said openings in the key changing 20 position of said member, tumbler members to be disposed in said openings and recesses, said recesses receiving the surplus tumbler members when a key is inserted in the key operable member in the key changing position 25 thereof, means in the body cooperable with said openings of the key operable member and tumbler members therein, in the operative position of the key operable member, for preventing said key operable member being operated excepting by the previously selected key, and releasable means for preventing the key operable member from being moved to key changing position, in combination 30 with a combination changing key insertable in said key operable member to control the last named means and tumbler members for moving the key operable member to combination changing position.

3. In a lock, a key operable member movable to operative and key changing positions, tumbler members to be carried by said key operable member, means for receiving the surplus tumbler members from the key operable member when a key is inserted with

the key operable member in key changing position, means cooperable with the tumbler members carried by the key operable member when the key operable member is in operative position to prevent said key operable member being operated excepting by the previously selected key, and a member having a clutch connection with the key operable member and limited in its movement to prevent the key operable member being moved to key changing position, in combination with a combination changing key corresponding with such previously selected key and having a portion arranged to disconnect the last named member and key operable member.

4. In a lock, a key cylinder arranged to be turned to operative and key changing positions, tumbler members to be carried by said cylinder in different selected combinations, means for receiving the surplus tumbler members from said cylinder when a key is inserted with the cylinder in key changing position, means cooperable with the tumbler members carried by said cylinder when the cylinder is in operative position to prevent said cylinder from being operated excepting by the previously selected key, and releasable means for preventing the cylinder from being turned to key changing position, in combination with a combination changing key corresponding with the aforesaid selected key to turn the key cylinder and release the last named means.

5. In a lock, a body, a key cylinder rotatable therein to operative and key changing positions, and having openings, the body having recesses for the registration of said openings in the key changing position of the cylinder, tumbler members to be disposed in said openings and recesses, said recesses receiving the surplus tumblers when a key is inserted in the cylinder in the key changing position thereof, means in the body cooperable with said openings and the tumbler members therein, in the operative position of the cylinder, for preventing the cylinder being operated excepting by the previously selected key, and releasable means for preventing the cylinder from being turned to key changing position in combination with a combination changing key corresponding with said previously selected key to turn the cylinder and release the last named means.

6. In a lock, a key operable member movable to operative and key changing positions, tumbler members to be carried by said key operable member, means for receiving the surplus tumbler members from the key operable member when an operating key is inserted with the key operable member in key changing position, means cooperable with the tumbler members carried by the key operable member when the key operable

member is in operative position to prevent said key operable member being operated excepting by the previously selected operating key, and means for preventing the key operable member being moved to key changing position, in combination with a combination changing key corresponding with the previously selected operating key for moving the key operable member and cooperable with the last named means to release the key operable member for movement to key changing position.

7. In a lock, a body, a key operable member movable in said body to operative and key changing position and having openings, the body having recesses for the registration of said openings in the key changing position of said member, tumbler members to be disposed in said openings and recesses, said recesses receiving the surplus tumbler members when a key is inserted in the key operable member in the key changing position thereof, means in the body cooperable with said openings of the key operable member and tumbler members therein, in the operative position of the key operable member, for preventing said key operable member being operated excepting by the previously selected key, and means for preventing the key operable member being moved to key changing position, in combination with a combination changing key corresponding with the previously selected key to operate the key operable member and cooperable with the last named means for releasing the key operable member for movement to key changing position.

8. In a lock, a key operable member movable to operative and key changing positions, tumbler members to be carried by said key operable member, means for receiving the surplus tumbler members from the key operable member when a key is inserted with the key operable member in key changing position, means cooperable with the tumbler members carried by the key operable member when the key operable member is in operative position to prevent said key operable member being operated excepting by the previously selected key, and a member having a clutch connection with the key operable member and limited in its movement to prevent the key operable member being moved to key changing position, in combination with a combination changing key corresponding with said previously selected key for operating the key operable member and cooperable with the last named member to disconnect said last named member and key operable member for the movement of the key operable member to key changing position.

9. In a lock, a key cylinder arranged to be turned to operative and key changing positions, tumbler members to be carried by said

cylinder in different selected combinations, means for receiving the surplus tumbler members from said cylinder when a key is inserted with the cylinder in key changing position, means cooperable with the tumbler members carried by said cylinder when the cylinder is in operative position to prevent said cylinder from being operated excepting by the previously selected key, and means for preventing the cylinder from being turned to key changing position, in combination with a combination changing key corresponding with the aforesaid selected key to turn the cylinder and cooperable with the last named means to free the cylinder for movement to key changing position.

10. In a lock, a body, a key cylinder rotatable therein to operative and key changing positions, and having openings, the body having recesses for the registration of said openings in the key changing position of the cylinder, tumbler members to be disposed in said openings and recesses, said recesses receiving the surplus tumbler members when a key is inserted in the cylinder in the key changing position thereof, means in the body cooperable with said openings and the tumbler members therein, in the operative position of the cylinder, for preventing the cylinder being operated excepting by the previously selected key, and means for preventing the cylinder from being turned to key changing position, in combination with a combination changing key corresponding with said previously selected key for operating the cylinder and having a portion cooperable with the last named means to free the cylinder for movement to key changing position.

11. In a lock, a body, a key operable member movable in the body to operative and key changing positions, and having openings, the body having recesses for the registration of said openings in the key changing position of said member, tumbler members to be disposed in said openings and recesses, said recesses receiving the surplus tumbler members from said key operable member when a key is inserted in the key operable member in the key changing position thereof, means in the body cooperable with said openings and tumbler members therein when the key operable member is in operative position to prevent said key operable member being operated excepting by the previously selected key, and a member having a clutch connection with the key operable member and limited in its movement to prevent the key operable member being moved to key changing position in combination with a combination changing key corresponding with such previously selected key and having a portion arranged to disconnect the last named member and key operable member.

12. In a lock, a body, a key operable member movable in the body to operative and key changing positions, and having openings, the body having recesses for the registration of said openings in the key changing position of said member, tumbler members to be disposed in said openings and recesses, said recesses receiving the surplus tumbler members from said key operable member when a key is inserted in the key operable member in the key changing position thereof, means in the body cooperable with said openings and tumbler members therein when the key operable member is in operative position to prevent said key operable member being operated excepting by the previously selected key, and a member having a clutch connection with the key operable member and limited in its movement relatively to the body to prevent the key operable member being moved to key changing position, in combination with a combination changing key corresponding with such previously selected key for operating the key operable member and having an extension arranged to disconnect the last named member and key operable member for the movement of the key operable member to key changing position.
13. In a lock, a key cylinder arranged to be turned to operative and key changing positions, tumbler members to be carried by said cylinder, means for receiving the surplus tumbler members from the cylinder when a key is inserted with the cylinder in key changing position, means cooperable with the cylinder and tumbler members carried thereby when the cylinder is in operative position to prevent the cylinder being operated excepting by the previously selected key, and a member having a clutch connection with the cylinder and limited in its turning movement to prevent the cylinder being turned to key changing position excepting by a combination changing key corresponding with such previously selected key and having a portion arranged to disconnect the last named member and cylinder.
14. In a lock, a key cylinder arranged to be turned to operative and key changing positions, tumbler members to be carried by said cylinder, means for receiving the surplus tumbler members from the cylinder when a key is inserted with the cylinder in key changing position, means cooperable with the cylinder and tumbler members carried thereby when the cylinder is in operative position to prevent the cylinder being operated excepting by the previously selected key, and a member having a clutch connection with the cylinder and limited in its turning movement to prevent the cylinder being turned to key changing position, in combination with a combination changing key corresponding with such previously selected key for operating the cylinder and having an extension to contact with the last named member for disconnecting said last named member and cylinder so that the cylinder can be turned to key changing position.
15. In a lock, a body, a key cylinder rotatable in the body to operative and key changing positions, and having openings, the body having recesses for the registration of said openings when the cylinder is in key changing position, tumbler members in said openings said recesses receiving the surplus tumbler members from said openings when a key is inserted in the cylinder in the key changing position thereof, means in the body cooperable with said openings and tumbler members therein when the cylinder is in operative position to prevent said cylinder being operated excepting by the previously selected key, and a member having a clutch connection with the cylinder and limited in its movement relatively to the body to prevent the cylinder being turned to key changing position, in combination with a combination changing key corresponding with such previously selected key and having a portion arranged to disconnect the last named member and cylinder.
16. In a lock, a body, a key cylinder rotatable in the body to operative and key changing positions, and having openings, the body having recesses for the registration of said openings when the cylinder is in key changing position, tumbler members in said openings said recesses receiving the surplus tumbler members from said openings when a key is inserted in the cylinder in the key changing position thereof, means in the body cooperable with said openings and tumbler members therein when the cylinder is in operative position to prevent said cylinder being operated excepting by the previously selected key, and a member having a clutch connection with the cylinder and limited in its turning movement relatively to the body to prevent the cylinder being turned to key changing position, in combination with a combination changing key corresponding with the previously selected key for operating the cylinder and having an extension to contact with the last named member for disconnecting said last named member and cylinder so that the cylinder can be turned to key changing position.
17. In a lock, a key operable member movable to operative and key changing positions, tumbler means for preventing the operation of said member when in operative position excepting by a proper key and adapted to be changed, when said member is in key changing position, to require a new key, and means for preventing the movement of said member from operative to key changing position and controllable by a different key inserted in said member to release said mem-

ber for movement to key changing position.

18. In a lock, a key operable member movable to operative and key changing positions, tumbler means for preventing the operation of said member when in operative position excepting by a proper key and adapted to be changed, when said member is in key changing position, to require a new key, and means for preventing said member from being moved from operative to key changing position, in combination with a combination changing key corresponding with the required first named key for operating said member and cooperable with the last named means for releasing said member for movement to key changing position. 70

19. In a lock, a body, a key operable member movable in the body to operative and key changing positions, tumbler means in said body and member for preventing the operation of said member when in operative position excepting by a proper key and adapted to be changed, when said member is in key changing position, to require a new key, and means for preventing said member being moved from operative to key changing position and controllable by a different key inserted in said member to release said member for movement to key changing position. 80

20. In a lock, a body, a key operable member movable in the body to operative and key changing positions, tumbler means in said body and member for preventing the operation of said member when in operative position excepting by a proper key and adapted to be changed, when said member is in key changing position, to require a new key, and means for preventing said member from being moved from operative to key changing position, in combination with a combination changing key corresponding with the required first named key for operating said member and cooperable with the last named means to release said member for movement to key changing position. 90

21. In a lock, a key cylinder movable to operative and key changing positions, tumbler means for preventing the operation of said cylinder when in operative position excepting by a proper key and adapted to be changed, when said cylinder is in key changing position, to require a new key, and means for preventing said cylinder being moved from operative to key changing position and controllable by a different key inserted in said cylinder to release said cylinder for movement to key changing position. 100

22. In a lock, a key cylinder movable to operative and key changing positions, tumbler means for preventing the operation of said cylinder when in operative position excepting by a proper key and adapted to be changed, when said cylinder is in key changing position, to require a new key, and means for preventing said cylinder from being moved from operative to key changing position, in combination with a combination changing key corresponding with the required first named key for operating said cylinder and cooperable with the last named means to release said cylinder for movement to key changing position. 110

for preventing said cylinder from being moved from operative to key changing position, in combination with a combination changing key corresponding with the required first named key for operating said cylinder and cooperable with the last named means to release said cylinder for movement to key changing position. 120

23. In a lock, a body, a key cylinder mounted for turning movement in the body to turn to operative and key changing positions, tumbler means in said body and cylinder for preventing the operation of said cylinder when in operative position excepting by a proper key and adapted to be changed, when said cylinder is in key changing position, to require a new key, and means for preventing the cylinder from being turned in the body from operative to key changing position and controllable by a different key inserted in said cylinder to release the cylinder for movement to key changing position. 130

24. In a lock, a body, a key cylinder mounted for turning movement in the body to turn to operative and key changing positions, tumbler means in said body and cylinder for preventing the operation of said cylinder when in operative position excepting by a proper key and adapted to be changed, when said cylinder is in key changing position, to require a new key, and means for preventing said cylinder from being turned from operative to key changing position, in combination with a combination changing key corresponding with the required first named key for operating the cylinder and cooperable with the last named means to release the cylinder for movement to key changing position. 140

25. In a lock, a key operable member movable to operative and key changing positions, tumbler means for preventing the operation of said member when in operative position excepting by a proper key and adapted to be changed, when said member is in key changing position, to require a new key, and a member having a clutch connection with the key operable member and limited in its movement to prevent the key operable member being moved to key changing position and controllable to release the key operable member for movement to key changing position. 150

26. In a lock, a key operable member movable to operative and key changing positions, tumbler means for preventing the operation of said member when in operative position excepting by a proper key and adapted to be changed, when said member is in key changing position, to require a new key, and a member having a clutch connection with the key operable member and limited in its movement to prevent the key operable member being moved to key changing position, in combination with a combination changing key corresponding with the required first named key for operating the member and cooperable with the last named means to release the member for movement to key changing position. 160

key corresponding with the required first named key for operating said member and cooperable with the last named member to disconnect it from the key operable member for the movement of the key operable member to key changing position.

27. In a lock, a body, a key operable member movable in the body to operative and key changing positions, tumbler means in said body and member for preventing the operation of said member when in operative position excepting by a proper key and adapted to be changed, when said member is in key changing position, to require a new key, and an unlocking member having a clutch connection with the key operable member and limited in its movement relatively to the body for preventing the key operable member from being moved to key changing position and controllable to disconnect said members for releasing the key operable member for movement to key changing position.

28. In a lock, a body, a key operable member movable in the body to operative and key changing positions, tumbler means in said body and member for preventing the operation of said member when in operative position excepting by a proper key and adapted to be changed, when said member is in key changing position, to require a new key, and an unlocking member having a clutch connection with the key operable member and limited in its movement relatively to the body for preventing the key operable member from being moved to key changing position, in combination with a combination changing key corresponding with the required first named key for operating said member and having a portion to disengage the unlocking member from the key operable member for the movement of the key operable member to key changing position.

29. In a lock, a key cylinder rotatable to operative and key changing positions, tumbler means for preventing the operation of said cylinder when in operative position excepting by a proper key and adapted to be changed, when the cylinder is in key changing position, to require a new key, and a member having a clutch connection with said cylinder and limited in its turning movement to prevent the cylinder being turned to key changing position and controllable to release the cylinder for movement to key changing position.

30. In a lock, a key cylinder rotatable to operative and key changing positions, tumbler means for preventing the operation of said cylinder when in operative position excepting by a proper key and adapted to be changed, when the cylinder is in key changing position, to require a new key, and a member having a clutch connection with said cylinder and limited to its turning

movement to prevent the cylinder being turned to key changing position, in combination with a combination changing key corresponding with the required first named key for operating said cylinder and having a portion to disengage said member from the cylinder for the movement of the cylinder to key changing position.

31. In a lock, a body, a key cylinder rotatable in the body to operative and key changing positions, tumbler means in said body and cylinder for preventing the operation of the cylinder when in operative position excepting by a proper key and adapted to be changed, when said cylinder is in key changing position, to require a new key, and an unlocking member having a clutch connection with said cylinder and limited in its turning movement relatively to the body for preventing the cylinder being turned to key changing position, and controllable to disconnect said member from the cylinder to release the cylinder for movement to key changing position.

32. In a lock, a body, a key cylinder rotatable in the body to operative and key changing positions, tumbler means in said body and cylinder for preventing the operation of the cylinder when in operative position excepting by a proper key and adapted to be changed, when said cylinder is in key changing position, to require a new key, and an unlocking member having a clutch connection with said cylinder and limited in its turning movement relatively to the body for preventing the cylinder being turned to key changing position, in combination with a combination changing key corresponding with the required first named key for operating said cylinder and having a portion to disengage said member from the cylinder to release the cylinder for movement to key changing position.

33. In a lock, a body, a key cylinder mounted in the body for rotary and axial movements, tumbler means in said body and cylinder for preventing the movement of the cylinder excepting by a proper key, a latch, and an unlocking member movable with the cylinder to be moved axially with the cylinder into and out of connection with the latch and to be turned with the cylinder for operating the latch, said unlocking member being arranged to be disconnected from said cylinder by a key inserted in said cylinder.

34. In a lock, a body, a key cylinder mounted in the body for rotary and axial movements, tumbler means in said body and cylinder for preventing the operation of said cylinder excepting by a proper key, a latch mounted for turning movement, and unlocking means arranged for either connecting the cylinder with the latch by the axial movement of the cylinder to turn the

latch with the cylinder or to be disconnected from the cylinder by a key inserted in said cylinder.

35. In a lock, a body, a cylinder mounted in the body for rotary and axial movements, tumbler means in the body and cylinder for preventing the operation of said cylinder excepting by a proper key, a latch, an unlocking member having a clutch connection with the cylinder, and spring means for holding said unlocking member and cylinder in engagement and for moving the unlocking member out of engagement from the latch, said unlocking member being movable axially with the cylinder to engage the latch and to move the latch by the turning movement of the cylinder.

36. In a lock, a body, a key cylinder mounted in the body for turning and axial movements, tumbler means in the body and cylinder for preventing the operation of said cylinder excepting by a proper key, a pivot pin carried by the body, a latch mounted to turn on said pin, an unlocking member having a clutch connection with the cylinder and movable axially with the cylinder to engage the latch, and spring means for separating the unlocking member and latch and holding the unlocking member and cylinder in engagement, the unlocking member being engageable with said pin when said unlocking member is disengaged from the cylinder.

37. In a lock, a body, a key operable member slidable in the body, a second member slidable in the body parallel with the key operable member, tumbler pins in the second member, said members being connected to move in unison, the body having openings to receive said pins for preventing the movement of said members, and tumbler members in the key operable member to register with said openings for moving said pins into the second member when the required key is inserted in the key operable member.

38. In a lock, a body, a key operable member slidable in the body, a second member slidable in the body parallel with the key operable member, said members being connected to move in unison, said members and body having openings to register, tumbler pins in the second member to move into the openings of the body, and tumbler members in the openings of the key operable member and body for moving said pins into said second member when the required key is inserted in the key operable member.

39. In a lock, a body, a key cylinder mounted in the body for rotary and axial sliding movements, a member slidable in the body and having a swivel connection with the cylinder to move slidably with the cylinder, tumbler pins in said member to engage in the body for preventing sliding movement of said cylinder and member, and

tumbler members in said cylinder and body to move said pins into said member when the required key is inserted in the cylinder.

40. In a lock, a body, a key cylinder mounted in the body for turning and axial sliding movements, a member slidable in the body spaced from said cylinder and having a swivel connection with said cylinder to slide with the cylinder, said cylinder, member and body having openings to register, tumbler pins in the openings of said member to enter the openings in the body for preventing sliding movement of said cylinder and member, and tumbler members in the openings of said cylinder and body for moving the pins into said member when the required key is inserted in the cylinder.

41. In a lock, a body, a key cylinder rotatable and slidable axially in said body, a member slidable in the body and having a swivel connection with the cylinder to slide with the cylinder, tumbler pins in said member and engageable in the body to prevent sliding movement of said cylinder and member, tumbler members in the cylinder and body for moving said pins into said member when the required key is inserted in the cylinder, a latch, and an unlocking member movable with the cylinder to be slid with the cylinder into connection with the latch for the operation of the latch by the turning movement of the cylinder.

42. In a lock, a body, a key cylinder slidably axially in the body and rotatable therein to operative and key changing positions, a plunger slidable in the body and having a swivel connection with the cylinder to slide with the cylinder, tumbler pins in the plunger engageable in the body to prevent sliding movement of said cylinder and plunger, tumbler members in the cylinder and body and cooperable with said pins when the cylinder is in operative position for moving the pins into the plunger when the required key is inserted in the cylinder.

43. In a lock, a body, a key cylinder slidably axially in the body and rotatable therein to operative and key changing positions, a plunger slidable in the body and having a swivel connection with the cylinder to be slid with the cylinder into connection with the latch for moving the latch by the turning movement of the cylinder, said unlocking member being limited in its movement relatively to the body to prevent the cylinder being turned to key changing position, and said unlocking member being controllable to disengage it from the cylinder to permit the cylinder to be turned to key changing position.

44. In a lock, a body, a key cylinder slidably axially in the body and rotatable therein to operative and key changing positions, a plunger slidable in the body and having a swivel connection with the cylinder to

- slide with the cylinder, tumbler pins in the plunger engageable in the body to prevent sliding movement of said cylinder and plunger, tumbler members in the cylinder and body and cooperable with said pins when the cylinder is in operative position for moving the pins into the plunger when the required key is inserted in the cylinder, said tumbler members being adapted to be changed when the cylinder is in key changing position so as to require a new key, a latch, and an unlocking member having a clutch connection with the cylinder to be slid with the cylinder into connection with the latch for moving the latch by the turning movement of the cylinder, said unlocking member being limited in its movement relatively to the body to prevent the cylinder being turned to key changing position, in combination with a combination changing key corresponding with the first named required key to operate said cylinder and having an extension to move the unlocking member out of connection with the cylinder to release the cylinder for movement to key changing position.
44. In a lock, a body, a key cylinder slideable axially with the body and rotatable therein to operative and key changing positions, a plunger slideable in the body and having a swivel connection with the cylinder to slide therewith, tumbler pins slideable in the plunger and engageable in the body to prevent sliding movement of said cylinder and plunger, the cylinder and body having openings, tumbler members in said openings to cooperate with said pins when the cylinder is in operative position for moving the pins into the plunger when the required key is inserted in the cylinder, the body having recesses with which the openings of the cylinder register when the cylinder is turned to key changing position, said recesses receiving surplus tumbler members from the cylinder when a key is inserted in the cylinder with the cylinder in key changing position, a latch, an unlocking member having a clutch connection with the cylinder to be moved with the cylinder into connection with the latch for moving the latch by the turning movement of the cylinder, and spring means for moving said unlocking member out of connection with the latch and for holding the unlocking member in engagement with the cylinder, said unlocking member being limited in its turning movement to prevent the cylinder being turned to key changing position unless said unlocking member is disengaged from the cylinder to release the cylinder, in combination with a combination changing key corresponding with the previously selected required key to operate the cylinder and having an extension to contact with and move the unlocking member out of engagement with the cylinder to release the cylinder for movement to key changing position.
45. In a lock, a key operable member movable to operative and key changing positions, tumbler means for preventing the operation of said member when in operative position excepting by a proper key and adapted to be changed, when said member is in key changing position, to require a new key, and means for normally preventing said member being moved to key changing position and controlled by a different key inserted in said member to permit said member to be moved to key changing position.
46. In a lock, a body, a key operable member movable in the body to operative and key changing positions, tumbler means in said body and member for preventing the operation of said member when in operative position excepting by a proper key and adapted to be changed, when said member is in key changing position, to require a new key, and means for normally preventing said member being moved to key changing position, in combination with a combination changing key insertable in said member and arranged to control the last named means to release said member for movement to key changing position.
47. In a lock, a body, a key cylinder slideable axially with the body and rotatable therein to operative and key changing positions, a plunger slideable in the body and having a swivel connection with the cylinder to release the cylinder for movement to key changing position.
48. In a lock, a key cylinder adapted to be turned to operative and key changing posi-

- tions, tumbler means for preventing the operation of said cylinder when in operative position excepting by a proper key and adapted to be changed, when the cylinder is 5 in key changing position, to require a new key, and means for normally preventing said cylinder being turned to key changing position and controlled by a different key inserted in said cylinder to permit said cylinder to be turned to key changing position. 10 49. In a lock, a body, a cylinder mounted for turning movement in the body to turn to operative and key changing positions, tumbler means in said body and cylinder for preventing the operation of said cylinder when in operative position excepting by a proper key and adapted to be changed, when said cylinder is in key changing position, to require a new key, and means for normally preventing said cylinder being turned to key changing position, in combination with a combination changing key insertable in said cylinder and arranged to control the last named means to release the cylinder for turning movement to combination changing position. 15 50. In a lock, a key operable member movable to operative and key changing positions, tumbler means for preventing the operation of said member when in operative position excepting by a proper key and adapted to be changed, when said member is in key changing position, by the insertion of a new key so as to require such new key when said member is returned to operative position, means operated by said member, and means for normally preventing the movement of said member to key changing position and controlled by a different key inserted in said member to release said member for movement to key changing position and to disconnect the second named means from said member. 20 51. In a lock, a body, a key operable member movable in the body to operative and key changing positions, tumbler means in said body and member for preventing the operation of said member when in operative position excepting by a proper key and adapted to be automatically changed, when said member is in key changing position, by the insertion of a new key so as to require such new key for operating said member after it is returned to operative position, means operated by said member, and means for normally preventing the movement of said member to key changing position, in combination with a combination changing key insertable in said member and arranged to control the second and third named means for disconnecting the second named means from said member and releasing said member for movement to key changing position. 25 52. In a lock, a key cylinder adapted to be turned to operative and key changing positions, tumbler means for preventing the operation of said cylinder when in operative position excepting by a proper key and adapted to be automatically changed, when said cylinder is in key changing position, by the insertion of a new key so as to require such new key to operate the cylinder after the cylinder is returned to operative position, and a member connected to said cylinder to turn therewith and limited in its turning movement to prevent the cylinder being turned to key changing position, said member being adapted to be disconnected from said cylinder by the insertion of a different key in the cylinder to permit the cylinder to be turned to key changing position. 30 53. In a lock, a body, a key cylinder mounted for turning movement in the body to turn to operative and key changing positions, tumbler means in the body and cylinder for preventing the operation of said cylinder when in operative position excepting by a proper key and adapted to be automatically changed, when said cylinder is in key changing position, by the insertion of a new key so as to require such new key to operate the cylinder after it is returned to operative position, and a member connected with the cylinder to turn therewith and limited in its turning movement to prevent the cylinder being turned to key changing position, in combination with a combination changing key insertable in the cylinder and arranged to disconnect said member from the cylinder to permit the cylinder to be turned to key changing position. 35 54. In a lock, a key operable member movable to operative and key changing positions, and means for normally preventing said member being moved to key changing position, in combination with a combination changing key insertable in said member and cooperable with said means to release said member for movement to key changing position. 40 55. In a lock, a rotatable key cylinder adapted to be turned to operative and key changing positions, and means for normally preventing said cylinder being turned to key changing position, in combination with a combination changing key insertable in said cylinder and cooperable with said means to release the cylinder for turning movement to combination changing position. 45 56. In a lock, a key operable member movable to operative and key changing positions, and means movable with said member and limited in movement to normally prevent said member being moved to key changing position, in combination with a combination changing key insertable in said member and cooperable with said means to disconnect said means from said member for the movement of said member to key changing position. 50

57. In a lock, a rotatable key cylinder, and a member connected with said cylinder to turn therewith and limited in its turning movement to prevent the cylinder being turned to key changing position, in combination with a combination changing key insertable in said cylinder and cooperable with

said member to disconnect it from the cylinder to permit the cylinder to be turned to key changing position.

10

In testimony whereof I hereunto affix my signature.

TERRY BRYAN MOREHOUSE.
